UNITED STATES PATENT OFFICE.

WALTER M. FISCHBACH, OF MILWAUKEE, WISCONSIN.

GUARD-RAIL STRUCTURE FOR TOY RAILWAY TRACKS.

Application filed December 11, 1924. Serial No. 755,284.

This invention relates to improvements in toy railways and more particularly to a guard rail structure designed for attachment to any of the ordinary types of tracks upon which toy trains are run, the purpose of the guard rail structure being to prevent the locomotive and cars drawn thereby tipping over and leaving the tracks of the railway in rounding curves, as well as when traveling upon straight sections of track approaching and leaving a curve. It is customary to manufacture these tracks in standard or uniform sizes or, in other words, to manufacture the tracks with standard distances between the rails, and, therefore, the present invention contemplates the provision of a guard rail structure which may be instantly adapted to a section of such a railway by being merely snapped into engagement with the same and without the employment of any extraneous fastening means or any tools whatsoever.

As stated above, it is customary to manufacture the railways in standard sizes and it is also customary to manufacture the locomotives and cars with their wheels so spaced as to adapt locomotives and cars of a number of different sizes, or more specifically, widths, to travel upon a railway of a definite size or gauge. Therefore, when a guard rail structure is provided in connection with such a railway, it is desirable that means be provided for spacing the guard rails a greater or less distance from the outer rail of the railway or track so that locomotives of different sizes may sweep along the guard rail in rounding curves, and, therefore, the present invention has as another object, to provide a guard rail structure embodying base members of such construction as to adapt them for application to the railway or track in a manner to suitably space the guard rail, supported thereon, with relation to the outer rail of the track, the invention contemplating, at the same time, a structure in which this adjustment may be effected without the necessity of adjusting individual parts or loosening and tightening connections, or employing tools of any nature whatsoever.

Another important object of the invention is to provide a guard rail structure in which the base or attaching members will be of such form that there can be no short circuiting of the rails of the track or railway.

Another object of the invention is to pro-

vide novel means whereby the base members of the guard rail structure may be supported in an elevated position where this is found desirable.

In the accompanying drawings:

Figure 1 is a perspective view illustrating one embodiment of the guard rail structure adapted to a section of track.

Figure 2 is a vertical transverse sectional view taken substantially on the line 2-2 of Figure 1, looking in the direction indicated by the arrows, and illustrating one manner of assembling the base member of the guard rail structure with the track.

Figure 3 is a similar view illustrating another manner of assembling the base member of the structure with the track.

Figure 4 is a view similar to Figure 2, illustrating a slight modification of the invention.

Figure 5 is a detail vertical transverse sectional view taken substantially on the line 5-5 of Figure 4, looking in the direction indicated by the arrows.

Figure 6 is a view similar to Figure 4, illustrating another modification of the invention, in which the base member of the guard rail structure is adapted to the ties of a railway or track.

Figure 7 is a vertical transverse sectional view taken substantially on the line 7-7 of Figure 6, looking in the direction indicated by the arrows.

Figure 8 is a perspective view illustrating a form of the invention in which the guard rail structure is supported in an elevated position.

Referring first to the embodiment of the invention illustrated in Figures 1, 2 and 3 of the drawings, the railway or track comprises the usual ties, indicated by the numeral 1, and the main rails 2 and third rail 3. These parts are of the usual construction and hence, need no specific description, except to say that the track is made in straight and curved sections which are adapted to be connected together end to end to make up the completed railway over which the toy train is to run, and the guard rail structure embodying the invention is adaptable to both the curved and straight track sections, as will be evident as the description of the invention progresses. The guard rail structure embodying the invention will be made up in sections corresponding, approximately, in length

60

2
to the length of the track sections now in common use, although it will be understood at this point that should it be desirable to do so, the guard rail structure may be made in a length to embrace any desired number of track sections. In any event, the structure comprises base members which are indicated in general by the reference numeral 4 and each of which is formed from an integral strip of metal possessing a desirable degree of resiliency. This strip is so formed, by bending or stamping operation, as to include a substantially flat end portion indicated by the numeral 5, into which is secured the lower end of an upright 6 having a bracket 7 projecting from that side thereof which is to be presented toward the outer one of the rails 2 of the track or railway section and supporting the guard rail, which is indicated by the numeral 8, and which is in the form of a strip of metal supported by one or more of the uprights 6 and the associated brackets 7, depending upon the length of the guard rail structure as a whole, the strip comprising the rail 8 being continuous and being smooth upon that side which is presented toward the track with which the guard rail structure is associated so that the side of the locomotive passing 30 the rail may move along the surface thereof without any obstruction being offered to the free travel of the locomotive. From the end portion 5, the strip comprising the base member is curved upwardly and thence extended horizontally as at 9, and beyond the portion 9 the strip is bent to provide a rail seat indicated in general by the numeral 10, and comprising a vertically extending portion 11, a rail base supporting portion 12 extending substantially horizontally from the portion 11, and a rail base flange engaging portion 13 which extends upwardly and inwardly toward the portion 11 and somewhat overhangs the rail base supporting portion 12. Beyond the portion 13, the strip is bent to provide a horizontally extending portion 14 and is thence bent back beneath the portion 14 and again bent as at 15, to provide an overhanging nose portion 16 located above and in spaced relation to a second rail base supporting portion which is indicated by the numeral 17 and which constitutes a horizontal extension from the bend 15. This formation of the strip of metal comprising the base member is duplicated adjacent the other end of the said strip so as to form a rail base seat including a vertical portion 18 corresponding to the portion 11, a rail base supporting portion 19 corresponding to the portion 12, a rail base flange engaging portion 20 corresponding to the portion 13, a bend 21 corresponding to the bend 14 and providing an overhanging base flange engaging nose 22 corresponding to the nose portion 16, and finally, a

70 rail base supporting portion 23 corresponding to the portion 17, it being observed by reference to Figures 1, 2 and 3 of the drawings, that the several rail base seats are oppositely arranged in the order in which they have been described, at opposite sides of the intermediate portion of the base member 10 as a whole. As will likewise be observed by reference to these figures, the said intermediate portion of the base member is 75 designed to extend beneath the third rail 3 of the railway or track section, and to insure against any short circuiting, the said intermediate portion of the strip is bent to provide a depression 24 which will result in 80 the said intermediate portion of the base member being spaced considerably below the said third rail 3. Outwardly beyond the vertical portion 18 of the rail seat comprising this portion and the portions 19 and 20, the strip is extended horizontally and thence downwardly and outwardly, as at 25, to provide a rest portion 26 designed to rest upon the surface upon which the structure is disposed.

85 At this point, it will be observed that by forming the strip comprising the base member, in the manner above described, the base member is provided with two relatively adjacent laterally presented rail base seats and two relatively remote upwardly presented rail base seats, the walls of the seats being 90 resilient because of the inherent resiliency of the metal comprising the base member.

95 Referring now to Figure 2 of the drawings, it will be readily understood that the base member may be readily and quickly adapted to the track section with which it is to be associated, by first engaging the outer base flange of one of the rails 2, for example, in the seat provided by the overhanging nose 21 and rail base supporting portion 23, and then snapping the base flanges of the other rail 2 into place between the portions 11 and 13 of the rail seat at the other end of the base member, and in this instance, it will be evident that if the last mentioned rail is engaged in the seat comprising the portions 11, 12 and 13, and which seat is next adjacent the guard rail 8, the guard rail will be located relatively close to the track. Should it be desired to locate the guard rail a greater distance from the track, this may be readily accomplished by 100 engaging the base of the outer rail of the track in the laterally opening seat which is next adjacent the seat comprising the portions 11, 12 and 13 adjacent the guard rail, as shown in Figure 3, and snapping the base of the other rail into engagement in 105 the seat comprising the portions 19 and 20. In this manner, not only is the base member adapted to be readily and conveniently 110 snapped into engagement with the track, but, furthermore, by a selection of the com- 115

100

105

130

panion seats in the said base member, the guard rail 8 may be positioned a greater or less distance from the track. In either event, the depressed intermediate portion 24 of the base member will be spaced from the third rail 3 to prevent any short circuiting.

It will also be evident from the foregoing description of this embodiment of the invention that when the base members of the 10 guard rail structure are snapped into engagement with the rails of the track sections, the uprights 6 will be firmly supported in upright position and will, in turn, firmly support the guard rail 8. It will also be 15 obvious that the structure as a whole may be manufactured at a low cost and the same is light in weight.

In the form of the invention illustrated in Figures 4 and 5 of the drawings, the 20 guard structure includes a base member which is indicated in general by the numeral 27 and is, as in the previously described form, formed from a single integral strip of sheet metal, bent, stamped, or otherwise 25 fashioned to provide a supporting portion 28 which is horizontally disposed and which supports an upright 29 corresponding to the upright 6 and provided with a bracket 30 supporting the guard rail which is indicated 30 by the numeral 31. The portion 28, in this form of the invention, is provided at its free extremity with a downwardly turned foot 32 having its lower portion turned outwardly, as at 33, to rest upon the surface upon 35 which the railway is disposed, and in order to reinforce the supporting portion 28, the same is preferably stamped or otherwise formed to provide longitudinally extending 40 beads 34 as clearly shown in Figure 5 of the drawings, the beads extending parallel to the longitudinal edges of the said portion 28 and terminating slightly short of the ends thereof. The opposite or inner end of the 45 portion 28 is turned downwardly as at 35, to provide one wall of a seat and beyond this portion the strip comprising the base member is extended horizontally, as at 36, to provide a rail base supporting portion, and thence is bent as at 37, upwardly and inwardly to provide a base flange engaging 50 nose 38 designed to overlie the flange of the rail of the track section which is engaged in the seat. At this point, it will be evident 55 by reference to both forms of the invention thus far described, that in engaging the base of a rail in the seat shown in Figure 4 or the corresponding seat shown in Figure 2, one side of the base flange is engaged beneath the nose 13 or the nose 38, as the 60 case may be, and the other side of the flange is then forced downwardly along the inwardly presented face of the portion 11 or the portion 35, the resiliency of the metal of which the base member, in either instance, 65 is formed, permitting of this ready adapta-

tion of the rail to the seats, or vice versa. From the nose 38, the strip comprising the base member is extended horizontally, as at 39, and thence vertically, as at 40, and then horizontally as at 41, so as to provide a depressed intermediate portion which is to 70 extend horizontally beneath the third rail of the track in spaced relation thereto to prevent short circuiting. At the other end of the portion 41, the strip is bent upwardly 75 at an angle and then horizontally to provide a rail base supporting portion 42, and thence inwardly upon itself as at 43, to provide a base flange engaging nose 44. Beyond the base flange engaging nose 44, the strip is extended horizontally, as at 45, and thence downwardly as at 46, and finally horizontally 80 as at 47, so as to provide a foot designed to rest upon the floor or other surface upon which the structure is disposed. It will be observed that in this form of the invention, the structure is incapable of adjustment with relation to the track sections, but the feature of prime importance is still present, namely, that of a guard rail structure embodying a base member adapted to be 85 instantly applied to a track section without the adjustment of movable parts, the use of extraneous fastening elements, or the employment of tools of any character whatsoever.

The feature above referred to is likewise present in the form of the invention which is illustrated in Figures 6 and 7 of the drawings, and in these figures the numeral 48 indicates in general the base member of the guard rail structure which, as in the previously described forms, is formed from a suitable integral length of sheet metal bent or otherwise worked to provide a horizontally disposed supporting portion 49 upon which is mounted an upright 50 corresponding to the upright 29 and provided with a bracket 51 supporting the guard rail indicated by the numeral 52. The strip from which the base member is formed is provided at its end which supports the guard rail upright 50, with a depending foot 53, and at the other end of the portion 49 the strip is bent to form a bluntly rounded nose indicated by the numeral 54. Immediately beneath the nose 54, the strip is bent to provide a horizontally extending portion 55 which is preferably reinforced by a stamped or otherwise formed longitudinally extending rib 56, and which has its free end portion bent back upon itself to provide a hook-shaped terminal 57. In this embodiment of the invention, the base member is adapted to be snapped onto the ties of the track and by reference to Figure 7, it will be observed that the ties are, as usual, formed of sheet metal and each tie, indicated in general by the numeral 58, comprises a rail supporting 120 125 130

portion 59 and depending side portions 60 extending along the longitudinal edges of the portion 59, the tie being open at its ends. In this embodiment of the invention, 5 the hook-shaped terminal 57 of the tie engaging portion 55, is engaged over one end of the tie, as shown in Figure 6, and the other end or edge of the supporting portion 59 of the tie is then depressed to ride 10 over the bulged side of the nose 54 and engage beneath the said nose as shown in said figure.

It will be observed that in all forms of the invention, the principle remains the 15 same, namely, that a portion or member of the track, as for example, one of the rails or one end of the tie is first engaged with an abutment which may be the nose 16 or nose 22 in Figure 2, or the nose 44 in Figure 4, or the hook-shaped terminal 57 in Figure 6, and the opposite side of the track 20 then caused to ride over a rounded shoulder and snapped into locking engagement with the base member of the guard rail structure. 25

In the embodiment of the invention shown in Figure 8 of the drawings, the guard rail structure includes a base member indicated in general by the numeral 61, and supporting an upright 62, in turn supporting the guard rail 63, and in this form, the base member 61 is substantially of the construction shown in Figures 1, 2 and 3 of the drawings, or it may be of the construction 30 shown in Figures 4 or 6 of the drawings, but in any event, it is provided at its opposite ends with outstanding flanges or foot portions indicated by the numeral 64. The numeral 65 indicates in general an elevated 35 support for the guard rail structure and consequently for the track associated therewith, and this support is preferably formed of sheet metal and comprises a flat supporting top 66, sides 67, and downwardly extending ends 68, the ends being provided 40 with side flanges 69 constituting downward extensions of the respective sides 67, and these extensions as well as the lower ends 45 of the ends 68 being provided with outstanding base portions 70 and 71 designed 50 to rest upon the floor or other surface upon which the structure is arranged. In order that the base member 61 may be securely anchored upon the flat top 66 of the supporting arch 65, said top 66 has tongues 72 struck up therefrom, and the flanges 64 of the base member 61 are engaged beneath these tongues by slightly flexing the base member 61 as a whole, thereby anchoring 55 the base member upon the said top 66.

In order that the base member 61 may be more securely held upon the supporting arch 65, the top 66 of the arch is preferably stamped or otherwise formed to provide 60 spaced longitudinally extending ribs 73 be-

tween which the portions of the base member which engage the upper surface of the top, may seat, as shown in the said Figure 8. It will be understood, of course, that in employing the arch members, they will be 70 made in various heights so that the track supported thereby may be gradually inclined from the lower portion of the track to highest one of the arches, and, therefore, some of the arches will have their tops 66 75 disposed at a greater or less angle of inclination although, otherwise, all of the arches will be substantially identical.

Having thus described the invention, what I claim is:

1. A guard rail structure for toy railways comprising a base member embodying a resilient seat to accommodate a member of the track to which the structure is to be adapted, and a guard rail supported upon 80 the base member.

2. A guard rail structure for toy railways comprising a base member embodying spaced seats having resilient walls, the seats constituting means for accommodating the rails of a track section with which the structure is to be assembled, and a guard rail supported upon the base member. 90

3. A guard rail structure for toy railways comprising a base member embodying spaced seats having resilient walls, the seats constituting means for accommodating the rails of a track section with which the structure is to be assembled, and a guard rail supported upon the base member, one of the said seats having its open side presented laterally toward the other seat, and the last mentioned seat having its open side presented upwardly. 100

4. A guard rail structure for toy railways comprising a base member of resilient material formed at intervals in its length to provide spaced seats to receive the rails of a track section to which the member is to be adapted, and a guard rail supported upon 105 the said base member.

5. A guard rail structure for toy railways comprising a base member consisting of a strip of resilient sheet metal formed at intervals in its length to provide a seat having its open side presented upwardly to accommodate one rail of a track section with which the member is to be associated and a second seat having its open side presented laterally toward the first mentioned seat and designed to accommodate one side of another rail of the said track section, and a guard rail supported upon the said base member. 115

6. A guard rail structure for toy railways comprising a base member consisting of a strip of resilient material formed at intervals in its length to provide seats to accommodate the rails of a section of track to which the structure is to be adapted, one of the seats comprising a rail base supporting portion 120

and a resilient base flange engaging nose overhanging the same, the other seat comprising a rail base supporting portion, a substantially perpendicular wall, and a rail base flange engaging nose presented toward said wall and overhanging the said supporting portion of the seat, and a guard rail supported upon the base member.

7. A guard rail structure for toy railways comprising a base member embodying spaced resilient seats to accommodate the rails of a track section to which the base member is to be adapted, the base member, between the said seats, being depressed to provide for spacing thereof from the third rail of the track section, and a guard rail supported upon the base member.

8. A guard rail structure for toy railways comprising a guard rail, a base member supporting the same and having a plurality of spaced sets of seats to selectively accommodate the rails of a track section to which the base is to be adapted, whereby the said guard rail may be supported at different distances from the track rails.

9. A guard rail structure for toy railways comprising a guard rail, and a base member supporting the same and having a plurality of spaced seats the walls of which are resilient and adapted to selectively accommodate the rails of a track section to which the base is to be adapted, whereby the said guard rail may be supported at different distances from the track rails.

10. A guard rail structure for toy railways comprising a guard rail, and a base member supporting the same and having a plurality of spaced sets of seats to selectively accommodate the rails of a track section to which the base is to be adapted, whereby the said guard rail may be supported at different distances from the track rails, one of the seats of one of the sets having its open side presented outwardly and the said seat including a substantially perpendicular wall, a rail base supporting portion, and a resilient base flange engaging nose presented toward the said wall and overhanging the supporting portion, the companion seat of the other set including a rail base supporting portion and a resilient rail flange engaging nose over-

hanging said portion, the open side of the last mentioned seat being presented toward the first mentioned seat.

11. A guard rail structure for toy railways comprising a guard rail, and a base member supporting the same and having a plurality of spaced sets of seats to selectively accommodate the rails of a track section to which the base is to be adapted, whereby the said guard rail may be supported at different distances from the track rails, one of the seats of one of the sets having its open side presented upwardly and the said seat including a substantially perpendicular wall, a rail base supporting portion, and a resilient base flange engaging nose presented toward the said wall and overhanging the supporting portion, the companion seat of the other set including a rail base supporting portion and a resilient rail flange engaging nose overhanging said portion, the open side of the last mentioned seat being presented toward the first mentioned seat, and the other companion seat of the set being reversely arranged with relation to the first mentioned companion seat and laterally displaced with relation thereto.

12. A guard rail structure for toy railways comprising a base member embodying resilient holding means to coact with the member of the track to which the structure is to be adapted, and a guard rail supported upon the base member, the guard rail supporting portion of the base member having longitudinally extending ribs reinforcing the same.

13. A guard rail structure for toy railways comprising an arched supporting member having a substantially flat top provided with spaced upstanding tongues presented toward each other, a base member comprising a strip of resilient sheet metal having flanges at its ends engageable beneath the tongues whereby to be held at its ends to the top of the said arch member, the strip having rail receiving seats therein to accommodate the rails of a track section, and a guard rail supported by the said base member.

In testimony whereof I affix my signature.

WALTER M. FISCHBACH.
